[57] **CLAIM**

The ornamental design for an earring, as shown and described.

DESCRIPTION

FIG. 1 is a bottom front perspective view of an earring showing my new designs;

FIG. 2 is a right front perspective view thereof;

FIG. 3 is a left side view of an earring showing a modified form of my new design wherein the clasp is reversed;

FIG. 4 is a rear perspective view of the first form with clasp open;

FIG. 5 is a rear perspective view of the second form with clasp open; and

FIG. 6 is a rear perspective view of the first form with the clasp closed.

FIG. 1.

FIG. 3.

FIG. 2.

FIG. 4.

FIG. 5.

FIG. 6.
